UNITED STATES PATENT OFFICE

2,597,593

DISPENSING CONTAINER WITH DETACHABLE SPOUT NESTABLE IN SAID CONTAINER IN NONUSE POSITION

Carl J. Neuner, Buffalo, N. Y.

Application February 16, 1948, Serial No. 8,549

3 Claims. (Cl. 222—479)

1

This invention relates to certain new and useful improvements in liquid dispensing containers and more particularly a container for receiving gasoline, kerosene or oil for use in automobile, marine and like engines.

It has for one of its objects to provide a container of this character which is so designed and constructed as to insure proper pouring of the contents without danger or spilling or leakage, and which embodies a detachable and self-contained pouring spout, thereby eliminating the use of a funnel.

Another object of the invention is to provide a liquid dispensing container which is easy, clean and convenient to use, which is simple and inexpensive in construction, and which in use affords maximum safety.

Other features of the invention reside in the construction and arrangement of parts herein-after described and particularly pointed out in the appended claims.

In the accompanying drawings:

Figure 1 is a perspective view of my improved container showing it in an operative or pouring position. Figure 2 is an enlarged sectional elevation thereof in a normal or inoperative position. Figure 3 is a fragmentary top plan view of the container, partly in section on line 3—3, Figure 2. Figure 4 is an enlarged, fragmentary vertical section showing the spout in a partially elevated position accessible for removal and use.

Similar characters of reference indicate corresponding parts throughout the several views.

In its preferred construction, my container consists of a cylindrical can body 10 of sheet metal or like material having a bail or handle 11 at its top for facilitating its carrying and having annular grooves 12 adjacent its top and bottom for conveniently grasping the can body and holding it against slippage during pouring. At its top and at one side of its center this can body has a combined filling and discharge opening 13 about which extends an externally-threaded neck 14 to receive a removable screw cap 15 having a flexible connection 16 joined at one end thereto and at its other end to the can body for holding the same captive to such body at all times.

Disposed axially of the can body or at the opposite side thereof containing the opening 13 and extending from top to bottom thereof in isolated relation to the contents thereof is a tube forming tubular chamber or compartment 17 which opens through the top of the can and about and above which rises an externally-

2

threaded neck 18 for receiving a screw cap 19 also retained captive to the can by a flexible connection 20. The cap-receiving neck 18 is of a larger diameter than the chamber 17 and a closure wall 21 spans the space therebetween. A vent 22 extends through the wall of this neck, opening at one end into the can body and at its other end into the atmosphere when the cap 19 is removed, so that during the pouring of the contents from the container air is permitted to enter the same.

Removably fitted in the chamber 17 for storage therein in an inverted position when not in use, as shown in Figure 2, is a pouring spout 23 which is adapted for operative connection to the discharge neck 14, as shown in Figure 1, when it is desired to pour the contents of the container into the fuel tank of a marine or like engine. This spout is preferably made of a flexible tubing terminating at its upper end in an enlargement or screw cap-like fitting 24 of a size for detachable connection to the threaded neck 14 and to nest or be housed within the neck 18 and retained therein by the screw cap 19. A spring 25 seated in the bottom of the spout-receiving chamber and abutting against the lower end of the spout serves to partially eject the latter from this chamber, when such cap 19 is removed, as shown in Figure 4, to facilitate grasping it for complete removal for pouring purposes. At its screw cap end this spout has a fine mesh filtering screen 26, while the bottom of such cap 24 has a gasket 27 fitted therein for sealing its connection to the discharge neck 14 when pouring. The screw caps 15 and 19 have gaskets 28 applied thereto for normally sealing their respective openings, and the gasket of the cap 19 further seals the vent 22 opening into the can body.

40 I claim as my invention:

1. A dispensing container of the character described, comprising a can body provided in its top with an opening disposed adjacent one side thereof and constituting a combined filling and discharge opening and a second opening therein remote from the first-named opening, threaded necks rising from the top of the can body about said openings, one of said necks being of larger diameter than the other, closure caps therefor, a tube disposed within said can body and forming a chamber in isolated relation to its contents and registering at its upper end with said second opening and having an ejecting spring in its lower end, and a spout removably housed in said chamber and adapted for operative pouring con-

nection to the discharge opening, said spout having a connecting means at one end thereof of a size to freely nest within the neck of said second opening when housed in said chamber and to engage the neck of the discharge opening in its pouring position, the other end of said spout abutting against said ejecting spring when housed in said chamber.

2. A dispensing container of the character described, comprising a can body provided in its top with an opening disposed adjacent one side thereof and constituting a combined filling and discharge opening and a second opening therein remote from the first-named opening, threaded necks rising from the top of the can body about 10 said openings, one of said necks being of larger diameter than the other, closure caps therefor, a tube disposed within said can body and forming a chamber in isolated relation to its contents and registering at its upper end with said second opening and having an ejecting spring in its lower end, and a spout adapted to be removably and invertedly housed in said chamber and for operative pouring connection to the discharge opening, said spout including a flexible tube provided at one end with a screw cap-like fitting of a size to freely nest within the neck of said second opening when housed in said chamber and to threadedly engage the neck of the discharge opening in its pouring position, the other end of 20 said spout abutting against said ejecting spring when housed in said chamber.

3. A dispensing container of the character described, comprising a can body provided in its top with an opening disposed adjacent one side thereof and constituting a combined filling and discharge opening and a second opening therein remote from the first-named opening, threaded 30

5 necks rising from the top of the can body about said openings, one of said necks being of larger diameter than the other, said larger diameter neck having a vent therein opening at one end into the can body and at its other end into the atmosphere, closure caps for said necks, the cap for the larger neck sealing the vent thereof in the non-use condition of the container, a tube disposed in said can body and forming a chamber in isolated relation to its contents and opening at its upper end within said larger neck, and a flexible spout removably housed in said chamber and adapted for operative pouring connection to the discharge opening, said spout being provided at one end with an attaching screw cap normally freely nested within said larger neck and adapted for operative screw-threaded connection to the companion neck of the discharge opening in its pouring position.
